CLAIM

The ornamental design for a pencil, as shown and described.

DESCRIPTION

FIG. 1 is a top plan view of the pencil showing my new design;

FIG. 2 is a front elevational view with the lead extending from the tip of the pencil, the rear elevational view being identical thereto; and,

FIG. 3 is a side elevational view with the lead retracted from the tip of the pencil, the opposite side elevational view being identical thereto.
